UNITED STATES PATENT OFFICE.

JOHN O. POOR, OF FRANKLIN, NEW HAMPSHIRE, ASSIGNOR, BY MESNE ASSIGNMENTS, TO HIMSELF AND RUFUS E. BEAN, OF SAME PLACE.

PAMPHLET-HOLDER.

SPECIFICATION forming part of Letters Patent No. 287,052, dated October 23, 1883.

Application filed June 5, 1883. (No model.)

To all whom it may concern:

Be it known that I, JOHN OSCAR POOR, of Franklin, in the county of Merrimac, of the State of New Hampshire, have invented a new and useful Improvement in Pamphlet-Holders; and I do hereby declare the same to be described in the following specification and represented in the accompanying drawings, of which—

Figure 1 is a back view, Fig. 2 an end view, and Fig. 3 a side view, of a pamphlet-holder embodying my invention, the nature of which is defined in the claims hereinafter presented. Fig. 4 is a perspective view of the devices for connecting the two covers of the pamphlet-holder and sustaining a pamphlet therein. Fig. 5 is a view of the holder as open and having a pamphlet arranged within it.

The mechanism for grasping the pamphlet consists of two wires or springs, A A, connected at their middles, and having each hooked at its opposite ends, as shown at a. To each wire spring, within its hooks, there is applied, so as to turn on it transversely of it, two of four hinge-leaves, B. Each pair of such leaves applied to a wire is riveted or otherwise fastened to one of two rectangular covers, C C. Instead of each wire being bent near each of its ends in the form of a hook, as shown, it may be bent in the form of an eye, or otherwise, properly, to enable the part so bent to answer as a jaw to hold the pamphlet D—which at its back is inserted between the pairs of hooks of the two wires—and is held in place

by the spring or elasticity of the wires. The covers readily turn open with or close upon the pamphlet, as occasion may require, in a manner analogous to that in which the covers of a book operate relatively to the leaves.

The article composed of the two covers, the hooked and connected springs, and the hinge-leaves, arranged and combined as set forth, is very convenient for holding a magazine or pamphlet, or a pack of leaves of paper or parchment.

In order to apply a pamphlet or magazine to the said article, the jaws of it are to be pressed apart and the pamphlet at its back is to be inserted between them. The springs being next allowed to compress the jaws upon the pamphlet, it will be securely held between the covers.

I claim—

1. The magazine or pamphlet holder, substantially as described, composed of the two covers, the hooked and connected springs, and the hinge-leaves, arranged and adapted essentially as set forth.

2. The covers-connection consisting of the two hooked or jawed and connected springs and the four hinge-leaves, arranged and adapted substantially as set forth.

JOHN OSCAR POOR.
